DRIER

William C. Glover, Jr., Raytown, Mo., assignor to
 Cleaners Specialties, Inc., Kansas City, Mo., a
 corporation of Missouri

Application July 9, 1938, Serial No. 218,461

5 Claims. (Cl. 34—106)

This invention relates to a garment drier particularly for use by dry cleaners, laundries, and similar establishments, for the drying and semi-finishing of garments, such as dresses, coats, and the like.

The principal object of the invention is to provide a simple and relatively inexpensive device of this character for securing the skirt portion of a garment and for blowing heated air into the interior thereof to substantially distend and shape the garment during drying thereof.

It is also an important object of the invention to provide a drier of this character with a garment carrier that is equipped with a plurality of garment suspending and supporting means that are alternately movable to and from drying position so that one garment may be applied while another garment is being dried.

It is a further object of the invention to provide an improved means for directing heated air into the garment and equipped with improved clamping means for securing the garment thereto.

In accomplishing these and other objects of the invention, as hereinafter pointed out, I have provided improved details of structure, the preferred form of which is illustrated in the accompanying drawings, wherein:

Fig. 1 is a perspective view of a garment drier embodying the features of the present invention, and showing one garment in position for drying and another garment after it has been applied and ready to be moved into drying position.

Fig. 2 is a similar view of the drier with the garments removed and showing the garment carrier in an intermediate position.

Fig. 3 is an enlarged section through the base of the drier and one of the nozzles on the garment carrier.

Fig. 4 is a section on the line 4—4 of Fig. 3.

Fig. 5 is a detail perspective view of the base of the drier showing the garment carrier removed therefrom.

Fig. 6 is a detail perspective view of one of the clamps for anchoring the skirt portion of a garment to one of the nozzles.

Fig. 7 is a sectional view through a part of the nozzle showing the clamp in side elevation.

Fig. 8 is a detail perspective view of a portion of the nozzle guard and air directing nozzle, particularly illustrating attachment of the guard.

Fig. 9 is a detail perspective view of one of the garment securing clips that is attached to the guards.

Referring more in detail to the drawings:

1 designates a garment drier constructed in accordance with the present invention, and which includes a base section 2 in the form of a housing having oppositely arranged side walls 3—4 and 5—6 connected together at the corners and reinforced at the bottom by an angle-member 7. The upper edges of the side walls are reinforced along their inner sides by an angle 8, having an inwardly directed flange 9 for supporting a top or cover plate 10. The cover plate 10 has a central opening 11 through which a blast of heated air is discharged, as later described. The lower portion of the side walls of the housing is provided with substantially arch-shaped openings 12 through which air is admitted into the housing, the inlet openings 12 being preferably covered by screens 13, as clearly shown in the drawings.

Extending across the interior of the housing between the side walls 5 and 6, in spaced relation with the wall 3, is an angle 14, having its ends welded to the inturned flanges of the angles 7 that extend along the side walls 5 and 6. The angle 14 cooperates with the angle 7 extending along the lower edge of the side wall 3, to support a motor carrying bracket 15. The motor carrying bracket includes spaced uprights 16 and 17, having their lower ends welded or otherwise secured to the flanges of the angle 14, and which have their upper ends braced from the cooperating angle 7 by brace arms 18. Fixed to the uprights 16 and 17 is an electric motor 19, having a vertically arranged armature shaft 20, carrying a propeller type fan 21 for drawing air through the openings 12 and discharging it under substantial pressure through the opening 11.

Supported above the fan 21, and below the opening 11 on angles 22 and 23 is a radiator unit 24, the angles 22 and 23 being secured to the inner faces of the side walls 3 and 4 so that the ends of inlet and outlet manifolds 25 and 26 are supported thereon and retained by the inwardly extending flanges of the angles 8, as clearly shown in Fig. 3. The radiator also includes a plurality of transverse tubes 27 interconnecting the respective manifolds so that a heating medium, such as steam, is circulated therethrough to heat the air blast discharged by the fan. The tubes 27 are preferably arranged in horizontal rows with the tubes in one row in staggered relation with the tubes in the other row, so that the air is directed against and across the sides of all of the respective tubes.

In order to increase the radiating capacity of the tubes and the contact surface thereof with

the air, the tubes are provided with spaced series of fins 28 as in conventional radiator construction. Steam is admitted to the radiator through a pipe 29, extending through the side wall 6 and welded into a suitable opening of the manifold 25 and the steam and condensate are discharged from the radiator by way of the manifold 26 through an L-fitting 30 having connection with a return line 31 that extends across the housing below the radiator and passes through a flanged opening 32 in the side wall 6.

Fixed to one corner of the housing is a sleeve-like bearing 33 having its upper end substantially aligning with the upper surface of the plate 10 for journaling a pin 34 that mounts the garment carrier or turntable 35.

The carrier 35 includes an elongated angle-frame 36 that conforms in width to the housing and is of substantially twice the length thereof to accommodate a pair of air directing nozzles 37 and 38 which are alternately movable over the opening 11 as later described. The frame 36 is covered by a plate 39 having openings 40 and 41 therein conforming in diameter to the opening 11. In order to reinforce the carrier, the frame also includes angle-iron diagonals 42 and 43 extending across the openings 40 and 41 and having their ends welded to the angle-iron frame as clearly shown in Fig. 5. The nozzles 37 and 38 are of substantially frustro-conical form and have their base portions welded to the plate 39 about the peripheries of the openings 40 so that the air discharged through the openings 11 into one of the nozzles is directed upwardly into a garment that is supported over cage-like guards 44 and 45.

The guards 44 and 45 are of dome-shape and include circumferential wires 46 of varying diameter and are connected by transverse wires 47 converging upwardly toward an apex 48. The lower circumferential wire substantially conforms to the inner diameter of the nozzles so that it is sleeved therein for attachment by suitable clips 49, as best shown in Fig. 8. Located about the peripheries of the nozzles are garment clamps 50 comprising arms 51 having their lower portions connected with the nozzles by hinges 52 that are spaced upwardly from the terminal ends thereof so as to provide stops 53 for limiting retractive movement of the clamps. The upper ends of the arms terminate in laterally extending clamping portions 54 having arcuate edges 55 covered with rubber or similar gripping material 56 to cooperate with similar gripping strips 57 that are attached to plates 58 carried by the transverse wires 47 of the guards. Connected with the lateral portions 54 of the arms are coil springs 59 having their lower ends anchored to the nozzles, as at 60, on the inner sides of the hinging points of the hinges whereby action of the springs exerts clamping pressure of the gripping strips 56 relatively to the strips 57 to clamp the skirt portion of a garment therebetween. The lateral portions of the clamps also carry knobs 61 by which the clamps may be moved retractively away from the clamping strips 57 so that the spring 59 moves across vertical dead center to the opposite side of the hinging points of the hinges to hold the clamps in retracted position as shown by the dotted lines in Fig. 7.

One or more of the upper circumferential wires of the guard may be provided with clothes pins 62 that are secured by clips 63 as best shown in Fig. 9. The clothes pins 62 are adapted to engage garments having skirt portions which are

too small to be extended about the lower periphery of the guards.

The pin 34 is fixed in a lug 64 extending from one side of the frame 36, and has a depending portion 34 journaled in the bearing 33 so that the lug 64 is supported for rotation on the upper end of the bearing. The opposite end of the pin projects above the lug 64 and sleeved thereover is the lower end of a tubular post 65 carrying a rod 66 having laterally extending arms 67 and 68 terminating over the axis of the nozzles in hooks 69 and 70 carrying depending chains 71 and 72 for adjustably attaching the hooks 73 of garment supporting hangers 74. The frame of the garment carrier is provided with stops 75 and 76 on the respective sides of the pivot pin to engage the housing and stop movement of the carrier when one or the other nozzles align with the openings 11.

In using a drier constructed and assembled as described, a garment, for example a coat, is applied to a hanger and the hook of the hanger engaged with the chain 71 so that the skirt portion of the coat overlaps the guards and is stretched downwardly thereover and over the sides of the nozzle in such a position that the clamping members 50 will cooperate with the clamping strips 57 to grip the garment when the clamping members are moved into clamping engagement therewith. When the clamping members are moved to clamping position the springs move across dead center and exert sufficient pressure to hold them in clamping position against pull of the garment. Steam having been turned into the radiator, the motor is started to blow air across the tubes of the radiator and through the nozzle into the garment, thereby distending and shaping the garment as shown in Fig. 1.

During drying of the coat, a dress or the like may be applied in similar manner to the other nozzle, as shown in Fig. 1. When the coat is dry, the carrier is swung on its pivot so that the dress is brought over the opening 11 and the heated air is discharged into the dress. The coat is then removed and another garment applied while the dress is being dried. When the dress is dried the movement of the carrier is reversed to move the dried dress out of position and the undried garment into position for drying, thus providing for continuous operation of the drier so that it is not necessary to stop the motor during application of a garment. Attention is directed to the fact that no time is lost by the operator in waiting for a garment to dry. By the time he has applied a garment to one side of the carrier, the garment on the opposite side is dried and ready for removal upon swinging the carrier so that the dry garment is swung out of drying position and the wet garment into drying position.

From the foregoing it is apparent that I have provided a simple and relatively inexpensive drier which is of continuous operation and well adapted for use of dry cleaners, laundries, and other places where it is necessary to dry and partially finish garments of the character described.

What I claim and desire to secure by Letters Patent is:

1. A drier of the character described including a housing having an air outlet opening in the top thereof, a radiator supported in the housing in covering relation with said opening, a fan supported in the housing for effecting discharge of air through the radiator and through said opening, a garment carrier having a plurality of air

directing nozzles, and means oscillatably mounting the garment carrier on the housing including a spindle member and a bearing member, one of said members being fixed to the garment carrier and offset laterally from a plane passing through the axes of both of said nozzles and the other substantially supported in the plane of the side wall of the housing whereby the garment carrier is adapted to be completely offset from said air outlet opening in one position of the 10 garment carrier and whereby one of said nozzles is moved from over said outlet opening and the other moved away from said air outlet opening in another position of the carrier.

2. A drier of the character described including a substantially rectangular housing having an opening in the top thereof, a radiator covering the opening, a fan in the housing for moving heated air through the opening, a garment carrier including a substantially rectangular member having a width to cover the housing and a length to accommodate a pair of nozzles substantially the size of said opening, and means oscillating the garment carrier on the housing including a spindle member and a bearing member, one of said members being mounted at a corner of the housing and the other at a side of the rectangular member in a plane passing midway between said nozzles whereby said nozzles may be selectively moved over the outlet opening and the entire carrier may be offset from covering relation with said opening.

3. In a drier, a housing having an air outlet opening, a garment carrier including a substan-

5 tially rectangular frame, diagonal brace members extending across said frame, a cover on the frame having a nozzle adapted to register with the air outlet opening in the housing, and means pivotally mounting said frame to the corner of said housing at the juncture point of one of the diagonal brace members with the frame.

4. In a drier of the character described including a substantially rectangular housing having an opening in the top thereof, a garment carrier including an elongated rectangular frame, a transverse member dividing the frame into sections substantially conforming to the size and shape of the housing, diagonals connecting the corners of said sections, a cover for the frame having openings substantially concentric with crossing points of said diagonals, and means pivotally connecting a side of the frame at the end of the transverse member with a corner of said housing whereby either one or the other of the openings in the garment carrier is adapted to align with the outlet opening of the housing.

5. A drier of the character described including, a housing having an air outlet opening in the top thereof, a sleeve-like bearing carried by the housing in offset relation to said opening, a garment carrier including a frame having nozzles adapted to be alternately registered with said opening in the housing, a pin carried by one side of the frame and swivelly mounted in said sleeve-like bearing, and a garment supporting post engaged over said pin.
